UNITED STATES PATENT OFFICE.

GEORGE H. RINEHART, OF ALLEGHENY, PENNSYLVANIA.

DESIGN FOR A BURIAL-CASKET.

Specification forming part of Design No. 7,757, dated September 15, 1874; application filed June 27, 1874.
[Term of Patent 3½ years.]

To all whom it may concern:

Be it known that I, GEORGE H. RINEHART, of the city and county of Allegheny and State of Pennsylvania, have invented a Design for Coffins, of which the following is a specification:

The design will first be hereinafter fully described, and then claimed.

I make a coffin with the double angles A, molding B, plain upper side and portions C, and the molding D, for the sides of top and

cover. These several forms, when taken together, make a "*tout-ensemble*" or novel design which is pleasing to the eye.

What I claim is—

The design for a coffin, substantially as shown and described.

GEORGE H. RINEHART.
